(57) CLAIM

The ornamental design for a shoe compartment for vehicles, as shown and described.

DESCRIPTION

FIG. 1 is a front, right side perspective view of a shoe compartment for vehicles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, right side perspective view with environment.

The broken lines in FIGS. 1-7 show portions of the article that form no part of the claimed design. The broken lines in FIG. 8 are provided for the purposes of illustrating environmental structure that form no part of the claimed design.

1 Claim, 6 Drawing Sheets
